UNITED STATES PATENT OFFICE.

JOSEPH W. ROBINSON, OF TOLEDO, OHIO.

CUT-OFF MEANS FOR METAL-GATHERING HEADS.

1,132,618.

Specification of Letters Patent. Patented Mar. 23, 1915.

Application filed April 17, 1914. Serial No. 832,486.

To all whom it may concern:

Be it known that I, JOSEPH W. ROBINSON, a citizen of the United States, and a resident of Toledo, in the county of Lucas and State of Ohio, have invented a certain new and useful Cut-Off Means for Metal-Gathering Heads; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to cut-off means for metal gathering heads or devices, and has particular reference to use in connection with that type of glass working machine in which the gathering mechanism is mounted on a moving support and has an arm, which carries a gathering head or device and is operable to periodically dip said head into the metal in a glass pot and then to withdraw it from the pot with the gathered metal. The invention is not restricted to this use, however, as it may be used in any connection for which it may be adapted or appropriate.

The object of my invention is the provision of simple and efficient means for use in connection with molten metal gathering heads or the like, and operable to cut-off or sever the surplus metal from the gathering head after being withdrawn from the metal in the pot, the metal being severed in such manner as to avoid, or nearly avoid, the leaving of teats or irregular surfaces on the exposed portion of the metal in the gathering head.

The invention is fully described in the following specification, and while, in its broader aspect, it is capable of embodiment in numerous forms, a preferred embodiment thereof is illustrated in the accompanying drawings, in which,—

Figures 1 and 2 are different elevations of a gathering head equipped with my invention, with the cut-off means in open position. Fig. 3 is a cross-section of the gathering head on the line α , α in Fig. 5. Fig. 4 is a bottom view of the gathering head and cut-off means with the latter open, and Figs. 5 and 6 are different central vertical sections of the gathering head illustrated with the cut-off means removed.

Referring to the drawings, 1 designates a gathering ram or arm of the type used in automatic glass working machines, and 2 the gathering head or vacuum cup at the outer end of the ram. The ram 1 is provided longitudinally therethrough with a passage 3 leading to any suitable source of suction creating means. The gathering cup 2 is fitted into the outer end portion of the ram 1 with its cavity in communication with the ram passage 3 through a slotted form of port 4, in the present instance, whereby a suction action may be created within the cup from the passage 3 when it is desired to draw a quantity of metal into the cup and retain it therein. It will be understood that this form of ram and gathering cup are conventionally shown and are merely for the purpose of illustration, and that the use of my improved cut-off means is not restricted to use in connection therewith.

The cut-off means comprises two knives 5, 5 which are carried at the free ends of respective arms 6, 6 and adapted to be swung under the open end of the gathering cup 2 from opposite sides thereof with their cutting edges in lapped shearing relation. The outer end of the gathering cup and the knives 5, 5 are each of arcuate form, being struck from the swinging center of the arms 6, 6 to enable the knives to swing under the cup in close cutting relation thereto. The arms 6, 6 are of inverted L-form or have their upper ends angled inwardly toward each other and carried by a common pivot 7, which is secured to the forward end portion of the ram 1 over the gathering cup 2. The pivoted ends of the arms 6 lap each other within a slot 8 in the gathering ram into which they project.

A shaft 9 is carried by the ram 1 transversely thereof and at the rear of the knife arms 6, 6, being journaled, in the present instance, in bearing brackets 10 rising from the top of the ram. An arm 11 fixedly projects forwardly from the shaft 9 between the brackets 10, and is provided at its forward or free end with a cross-arm 12 which is disposed substantially over the inwardly angled upper end portions of the knife arms 6, 6 and has connection therewith through the links 13, 13, one link being connected to each arm 6. The ends of the links 13 are in universal joint, or ball and socket, connection with the respective arms 6 and 12, as shown at 14, thus permitting the arm 11

when swung on one axis to communicate opposed simultaneous rocking movements to the arms 6, 6 on an axis which is at right angles to the axis 9. An arm 15 is fixed to 5 one end of the shaft 9 and has connection with any suitable actuating means through a link 16, which link forms a part of such means. As the means employed for actuating the movements of the arm 15 may be 10 of numerous forms, it is not thought necessary to show the same, especially as such means forms no part of the present invention. It is evident that the arms 11 and 15 and shaft 9 combine to form a bell-crank 15 type of lever. Upon a rearward movement of the link or draft-rod 16, from whatever cause, the arm 11—12 of the bell-crank lever is swung downward, thereby communicating an inward swinging movement to the knife 20 carrying arms 6 to cause the knives 5 to swing under the gathering end of the cup 2 and to have lapped shearing engagement at their inner or cutting edges. The cutting edges of the knives are preferably of 25 posed broadened V-form to facilitate the shearing action of the knives as they lap one another. After a cut has been made the parts are returned to their normal open position, as shown in Figs. 1, 2 and 4, by a 30 coiled contraction spring 17, which connects the draft-rod 16 to a point on the ram 1, or any other suitable means may be provided for the purpose.

I wish it understood that my invention is 35 not limited to any specific construction or arrangement of the parts as numerous modifications may be made without departing from the spirit thereof.

Having thus described my invention, 40 what I claim as new, and desire to secure by Letters Patent, is,—

1. The combination with a gathering cup, of a pair of arms pivoted to the upper closed end of the cup and extending outward and downward therefrom at opposite sides of the cup and having blades at their free ends for swinging in shearing relation under the cup when the arms are swung inward, and a single mechanism movable with 45 said cup and operable to impart opposed swinging movements in unison to said arms.

2. The combination with a ram and a gathering cup carried thereby, of a pair of L-shaped arms mounted at one end on a common pivot at the upper closed end of said cup and thence extending outward and downward at opposite sides of the cup and terminating at their free ends in transversely projecting blades for swinging under the lower open end of the cup in shearing relation when the arms are swung inward, a lever pivotally carried by said ram adjacent to the upper end of said cup for 60

rocking movements in a plane lengthwise of the ram and cup, connection between said 65 lever and each of said arms, and means for rocking the lever to impart inward and outward swinging movements to the arms.

3. The combination with a gathering cup, of a pair of arms mounted on a common 70 pivot at the upper closed end of said cup and extending outward and downward at opposite sides of the cup and terminating at their free ends in inwardly projecting blades for swinging in shearing relation under the lower open end of the cup, a lever pivoted adjacent to the top of said cup and having a T-arm, link connection between the free ends of said T-arm and the respective outwardly extending upper end portions of 75 said pivot arms for causing the like opposed swinging movements to be imparted in unison to said arms from a rocking of said lever, and means operable to rock said lever.

4. The combination with a gathering ram 85 and a gathering cup carried thereby, of a pair of arms pivoted to the cup adjacent to the closed end thereof and having shearing parts at their free ends for swinging under the open end of the cup in lapped shearing 90 relation when the arms are swung inwardly, a lever pivoted to the ram, draft means operable to move said lever, and link connection between said lever and each of said arms having universal joint connection with 95 the respective lever and arms.

5. The combination with a gathering cup, of a pivot disposed at the closed end thereof, arms carried by and projecting in opposed relation from said pivot and thence 100 lengthwise of the gathering cup at opposite sides thereof, knives carried by said arms at the free ends thereof and adapted to swing under the gathering end of the cup and to have lapped shearing engagement 105 when the arms are swung inwardly, said knives having broadened V-shaped cutting edges, a lever pivoted adjacent to said head with its pivot at right angles to the pivot of said arms, one arm of said lever 110 having a control member attached thereto and the other arm having a cross-head which is disposed above the inner end portion of said knife carrying arms, and links disposed between each of said knife carrying arms and the adjacent end portion of said cross-head and having universal joint 115 connection with the respective parts.

In testimony whereof, I have hereunto signed my name to this specification in the presence of two subscribing witnesses.

JOSEPH W. ROBINSON.
